Primary Examiner — Samantha Q Lawrence*Assistant Examiner* — Holly M Rodriguez(74) *Attorney, Agent, or Firm* — Egbert, McDaniel & Swartz, PLLC(57) **CLAIM**

The ornamental design for a television decoder, as shown and described.

DESCRIPTION

FIG. 1 is a top, front and right side perspective view of a television decoder showing my new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom, rear and right side perspective view thereof; and,

FIG. 9 is a bottom, rear and left side perspective view thereof.

The broken lines shown in FIGS. 1, 3, 6, 8 and 9 illustrate portions of the television decoder that form no part of the claimed design.

1 Claim, 9 Drawing Sheets(56)
